(57) **CLAIM**

The ornamental design for a capsule, as shown and described.

DESCRIPTION

FIG. 1 is a perspective view of a capsule showing my new design;

FIG. 2 is a right elevational view thereof;

FIG. 3 is a left elevational view thereof;

FIG. 4 is a rear elevational view thereof;

FIG. 5 is a front elevational view thereof;

FIG. 6 is a top plan view thereof;

FIG. 7 is a bottom plan view thereof;

FIG. 8 is an exploded perspective view of FIG. 1; and, FIG. 9 is an exploded perspective view of FIG. 1, shown in an open configuration with unclaimed interior portions removed.

The broken lines are shown for the purpose of illustrating portions of the capsule that form no part of the claimed design.
